UNITED STATES PATENT OFFICE.

LOUIS PAULERO, OF PETERSBURG, VIRGINIA, ASSIGNOR TO AMERICAN ELECTRIC TOOL COMPANY, INCORPORATED, OF PETERSBURG, VIRGINIA, A CORPORATION OF VIRGINIA.

ELECTRIC HAMMER.

Application filed December 5, 1917. Serial No. 205,503.

To all whom it may concern:

Be it known that I, LOUIS PAULERO, a citizen of the United States, and a resident of Petersburg, in the county of Dinwiddie and State of Virginia, have invented a new and useful Improvement in Electric Hammers, of which the following is a specification.

My invention relates to an improvement in electric hammers, being more particularly an improvement in the method of cooling the coils and cooperating parts, and it consists in the constructions, combinations, and arrangements herein described and claimed.

An object of my invention is to provide an electric hammer wherein a forced draft is maintained through the hammer casing and around the coils and cooperating parts, during the time that the hammer is in operation.

Another object of the invention is to provide an electric hammer including a fan driven solely by the reciprocating action of the plunger, thereby utilizing the back stroke of the plunger, the force of which was heretofore expended uselessly on the cushioning spring.

Another object of the invention lies in the novel construction of the trigger operated switch, which includes a pair of movable electrodes through the medium of which the circuits to the coils are simultaneously broken.

Other objects and advantages will appear in the following specification, reference being had in the accompanying drawings, in which:

Figure 1 is a central longitudinal section of the hammer.

Figure 2 is a detail enlarged section of the anvil and guide.

Figure 3 is a perspective view of the anvil guide.

Figure 4 is a cross section on the line 4-4 of Figure 1.

Figure 5 is a detail section showing one of the electrical connections on the casing head.

Figure 6 is a detail section of the fan and driving mechanism therefor.

Figure 7 is a cross section on the line 7-7 of Figure 6.

Figure 8 is a detail perspective view of the spiral driving bar, portions being disassembled.

Figure 9 is a cross section on the line 9-9 of Figure 6.

Figures 10 and 11 are cross sections on the lines 10-10 and 11-11 of Figure 1.

Figure 12 is a detail section of the switch.

Figure 13 is a plan view thereof.

Figure 14 is an enlarged detail section of a portion of the switch, and

Figure 15 is a diagrammatic view showing the connection of the switch in the solenoid magnet circuit.

The essential features of the invention reside in the manner of forcing a current of air around the solenoid magnet coils and the plunger, and in the peculiar manner of creating this current of air through the striking of the head of the spiral driving bar, by the plunger on the back stroke, and consequently rotating a fan in connection with the spiral driving bar. Portions of the invention illustrated in Figure 1 are disclosed in my co-pending application filed July 22, 1915, Serial Number 41399, patented December 14, 1920, No. 1,362,349. Before proceeding with the description of the essential features of the invention outlined above, it is thought advisable to describe the elements of the invention disclosed in the co-pending application.

Briefly then, a pair of solenoid magnet coils 1 and 2 are disposed inside of the casing 3 and wound upon a spool 4 of diamagnetic material such for instance, as brass. The coils 1 and 2 are energized alternately and act upon the plunger 5 which is thus caused to reciprocate rapidly in the bore 6 of the spool. The alternate energization of these coils is obtained by the special form of generator disclosed in the above stated application. These are the principal elements that appear in said application, and a further description other than that given, is thought unnecessary.

Proceeding now, with the description of the invention, the plunger 5 is provided with a plurality of relatively deep grooves 7 formed parallel to the axis of the plunger. These grooves permit the passage of the stream of air created in the bore 6, past

the plunger. The grooves also perform the valuable function of breaking up the eddy currents created by the coils 1 and 2.

An anvil 8 is located in front of the plunger 5 and is struck by the plunger on the forward reciprocations thereof. The anvil is carried by an anvil guide 9 which includes the threaded nose 10 having a bore 11. The body portion of the anvil moves in a counter bore 12, and a collar 13 on the anvil is normally forced against the annular shoulder formed at the junction of the bores, by a heavy coil spring 14.

The peripheral surface of the anvil guide 9 is longitudinally grooved at 15. The grooves 15 have radial extensions 16 in the collar 17 of the anvil guide. The purpose of the grooves 15 and 16 is to permit the current of air to flow into a space 18 surrounding the coils 1 and 2, from which it escapes to the outer atmosphere through a series of perforations 19 in the casing 3.

A fan 20 situated in a chamber 21 of the hammer head 22 is caused to rotate through the impact with a head 23 of a spiral driving bar 24, and thus create the current of air. Air is admitted to the chamber 21 through an opening 25. The spiral driving bar 24 comprises a piece of metal which is square on the front end and is given a quarter twist to form the spiral from whence it obtains its name.

Attention is directed more particularly to Figures 6 to 9, inclusive. The head 23 is hollow throughout its length and includes a square opening 27 by which the spiral driving bar 24 is admitted to the head 23. The head 23 has a collar 28 on the end adjacent to the square hole 27. The collar 28 rides in a counter bore 29 of a housing 30, and is prevented from turning therein by means of the engagement of a spline 31 in the collar 28, with a groove 32 in the counter bore 29.

A relatively light coil spring 33 presses the head 23 forwardly until the collar 28 rests against the shoulder 34 surrounding the opening in which the head 23 moves. The other end of the spring 33 rests on the vertical wall of a bore 35 in the housing 30 in which is also located, a heavy coil spring 36. The spring 36 is intended to receive and absorb the shocks imparted to the head 23 by the blows of the plunger 5. The spring 36 rests against the annular shoulder 37 formed at the juncture of the bores 29 and 35. The housing 30 is a separate member and is screwed into the casing head 38 at 39.

The head 23 upon being struck by the plunger 5 will move backwardly in the counter bore 29, compressing the spring 33 until the buffer spring 36 is reached, in the meantime giving a partial turn to the spiral driving bar 24. This partial turn is imparted

to the fan 20 by means of one or a plurality of pawls 39 which engage the ratchet teeth 40 in the hub 41 of the fan 20.

Each pawl 39 includes a relatively heavy round heel 42 which rests in a circular recess 43 in the head 44 of the spiral driving bar. The head 44 joins the spiral driving bar at the circular shank 45. It will be observed that the circular shank 45 and the square portion of the spiral driving bar meet at a groove 46 into which the ends of pins 47 mounted in the circular projection of the casing head 38, project. The pins 47 are held in place by a band or ring 49 which fits over the circular projection 48 and is held in place by a screw or pin 50.

A spring 51 mounted in a recess 52 in the plane continuation 53 of the circular recess 43, forces the pawl 39 outwardly and into engagement with the ratchet teeth 40. It will be observed that the pawl 39 depends solely on the heavy heel 42, for its maintenance in the circular recess 43, and that the pivot pin usually employed under similar circumstances, is omitted. Another feature lies in the arrangement of the circular recess 43 in the head 44. This recess is located well into the body of the head and consequently leaves a lip 43a which acts as an abutment for the pawl 39. The outer surface of the pawl is struck on an arc of substantially the same radius as that of the head 44, so that the pawl will be confined within the periphery of the head when urged to do so against the tension of the spring 51.

A cap 54 closes the end of the hub 41. The head 44 has a pintle 55 which occupies a recess 56 in the cap 54. Ball bearings 57 assist the easy rotation of the head 44. The cap 54, besides providing an end bearing for the spiral driving bar 24, also keeps the pawls 39 in their places. It will now be understood, that the partial rotation of the spiral driving bar 24, caused by the impact of the plunger 5 on the head 23, causes the fan 20 to rotate through the engagement of the pawls 39 with the ratchet teeth 40 on the hub 41. As soon as the plunger 5 recedes from the head 23, the spring 33 expands, driving the head 23 to its original position, and counter-rotating the spiral driving bar 24. The pawls 39 then merely drag back over the ratchet teeth 40 ready for another thrust, while the fan 20 continues to rotate under the influence of the momentum imparted thereto through the action just described.

A band 58 embraces the blades of the fan. The band moves closely to the wall of the chamber 21, and in a measure serves to direct the air current forwardly. Obviously, the band also braces and strengthens the fan.

The air from the fan 20 leaves the cham-

ber 21 and enters the space 18, through a plurality of segmental openings 59 in the casing head 38. The openings 59 are formed between webs 60 upon each of which, a current plug 61 is mounted. The casing head 38 is screwed into the hammer head 22 as shown. The hammer head 22 includes the externally threaded annular flange 62 which extends beyond the casing head 38. The casing head 38 is pressed tightly against the adjacent surface of a boss 4^a of the spool 4 when the parts are assembled so that the plug 61 will be in firm contact with the coacting socket 62 in the boss 4^a. The casing 3 and hammer head 22 are clamped together by a split ring 63 which includes the partly threaded portion 64 and the annular flange 65. The flange 65 engages an annular rib 3^a on the casing 3. A bolt 66 clamps the ends of the ring 63 together. The ring 63 is first partly tightened by means of the bolt 66, and then screwed on the threaded flange 62 until the flange 65 binds upon the rib 3^a, whereupon the bolt 66 is fully tightened, and the casing 3 is firmly clamped on the hammer head 22.

Segmental openings 67 in the boss 4^a, form continuations of the openings 59 in the casing head 38. The air stream passes through these aligned openings, and strikes an annular pyramidal partition 68 formed on the rear end of the spool 4. The air stream is separated here, a portion flowing into the outer space 18, and another portion flowing into the bore 6 of the spool 4 as indicated by the divided arrow in Figure 1.

The medial portion of the spool 4 has an air chamber 69 which surrounds the bore 6. A web 70 defines the limits of the air chamber. An air gap 71 is formed outside of the web 70, and holes 72 offer communication between the air chamber and the air gap. The purpose of the air chamber, holes and air gap, is to permit the free circulation of the air around the plunger 5 and the solenoid coils.

A tool 73 is fitted in a steel bushing 74 in the chuck 75 of the hammer. The casing 3 is screwed on the chuck 75, and the threaded nose 10 of the anvil guide 9 is screwed into the chuck as shown. A striker pin 76 of the anvil 8 abuts the end of the tool 73. Each forward impact of the plunger 5 is transmitted to the tool 73 through the anvil 8 and striker pin 76. The purpose of the spring 14 in the bore 11, is to receive the force of the blow of the plunger 5 when there is no tool in the chuck 75, and prevent damage to the chuck which would otherwise receive the blow were it not for the spring 14.

A novel form of switch is also embodied in this form of the invention. The position of the switch with relationship to the cir-

cuits of the coils 1 and 2, is shown in Figure 65 15. The construction of the switch is best shown in Figures 12 to 14 inclusive, to which attention is directed.

The switch comprises an insulating base 77 which is secured in the chamber 78 of the hammer head 22 and hidden from view by the cover plate 79. The base 77 has front and rear standards 80 and 81 which are preferably formed integrally with the base.

Two pairs of contacts 82 and 83 are mounted upon the base. The contacts 82 are secured on top of the standard 80 and include curved spring tips 82^a. The contacts 83 are bent to include a vertical portion 84 which lies against the standard 81 and forms a bearing for a shaft 85. Other portions of the contacts 83 are bent over the top of the standard 81 where they are secured, and bent to lie on the top of the base 83 where they terminate in spring tips 83^a 85 cooperating with the tips 82^a.

There are two of the shafts 85, but these as well as the associated mechanism, being of the same construction, a description of but one will be given. Each shaft 85 is mounted near one end of an electrode bridge 86 which is also made of insulating material and has a central pin 87 engageable by a trigger 88 through the medium of which the shafts and electrode bridge are moved 95 forwardly against the tension of a spring 89.

The front end of the shaft 85 is reduced to form a pintle 90. The pintle carries a hollow electrode 91 with an annular groove 92 on the periphery, and an adjacent beveled edge 93. A spring 94 is disposed inside of the electrode 91 and engages a head 95 on the pintle 90, at one end. The purpose of the spring 94, which is considerably weaker than the spring 89, is to permit a certain 105 latitude or freedom of motion of the shaft 85, after the electrode 91 is thrust between the spring tips of the contacts 82 and 83, when said spring tips press into the annular groove 92.

The wires leading to the switch and the coils 1 and 2, are conducted through a passage 96 in the handle 97 of the hammer head. A bushing 98 insulates the wires from the metal of the handle. The operation of the device is as follows:

The coils 1 and 2 are energized alternately by the means already described as being the subject matter of a pending application, whereupon, the plunger 5 being alternately attracted, is made to reciprocate very rapidly in the bore 6 of the diamagnetic spool 4. The anvil 8 and the head 23 are thus alternately struck. The impacts on the anvil 8 are transmitted to the tool 73. A 125 portion of the shock is absorbed by the spring 14. The spring 14 will absorb all of the shock in the event that the hammer is

started and the tool 73 is omitted through an oversight. The spring 14 is necessary to prevent damage to the chuck 75.

The impacts on the head 23 by the back reciprocations of the plunger 5, are expended in rotating the fan 20 through the medium of the spiral driving bar 24, and the pawl and ratchet devices 39 and 40, to force a current of air through the bore 6 and the space or 10 chamber 18 around the coils.

To facilitate the thorough circulation of the air, the annular pyramidal partition 68 is situated at the mouths of the segmental openings 67 of the casing head 38, whereby 15 the air current is divided, a part flowing into the space 18 and another part flowing into the bore 6.

The air thus divided, flows through the grooves 7 in the plunger 5, through the 20 grooves 15 and 16 of the anvil guide 9, and out of the perforations 19 in the casing 3. The air also circulates through the holes 72 in the web 70 of the spool 4, the ultimate 25 purpose of the circulating air being to carry away the excessive heat generated in the operation of the coils 1 and 2. As stated before, the longitudinal grooves 7 in the plunger 5, serve to destroy the eddy currents generated in the plunger under the action 30 of the coils.

Attention is again directed to the switch illustrated in Figure 12, et seq. The hollow electrodes 91 are moved forwardly simultaneously into engagement with the 35 spring tips 82 and 83, upon pressing of the trigger 88. Pressure must be maintained on the trigger to overcome the tension of the spring 89 and keep the electrodes in position between the contacts. In devices of 40 this kind, there is always a certain amount of vibration caused by the action of the plunger on the anvil, and it would be particularly difficult to keep the electrical contacts in firm engagement so that the continuity of the flowing current might not be 45 broken. The inefficient operation of the device by these recognized imperfections, is anticipated by mounting the electrodes 91 in relatively movable relationship to the 50 shafts 85, which thrust the electrodes forwardly and between the contacts.

The springs 94 permit a certain amount of reciprocatory vibration of the shafts 85, such as might come about by an unsteady 55 pressure on the trigger 88, or by other causes. It will readily be understood that the contacts will tightly grip the electrodes and yet the shafts 85 may play back and forth, the springs 94 acting as buffers. 60 When pressure on the trigger 88 is released entirely, the spring 89 which is much more powerful than the spring 94 of each unit, expands against the bridge 86, overcomes the tension of the contacts holding the electrodes

91, and breaks the circuit of both of the solenoid coils.

While the construction and arrangement of the device is that of a generally preferred form, obviously modifications and changes may be made without departing from the spirit of the invention or the scope of the claims.

I claim:

1. In an electric hammer, a reciprocating plunger, electromagnetic means for reciprocating the plunger, and rotatable means for forcing a current of air around the plunger and said electromagnetic means. 75

2. In an electric hammer, a reciprocating plunger, electromagnetic means for reciprocating the plunger, and rotatable means operating under the instrumentality of the plunger to create and force a current of air around the plunger and said electromagnetic means. 80

3. In an electric hammer, a plunger, electromagnetic means for reciprocating the plunger, and rotatable means impelled at alternate reciprocations of the plunger to create a current of air around the same. 90

4. In an electric hammer, a casing, a plunger having grooves, electromagnetic means encircling the plunger and in spaced relationship with the casing, said means effecting the reciprocation of the plunger, and 95 means including a rotatable air driving device arranged to receive alternate impacts of the plunger and adapted to create a current of air for circulation through the grooves and the space between said electromagnetic 100 means and the casing.

5. In an electric hammer, a reciprocating plunger, and a fan operated in intermittent rotational impulses upon alternate reciprocations of the plunger. 105

6. In an electric hammer, a reciprocating plunger, a fan operated in intermittent rotational impulses upon alternate reciprocations of the plunger, and an impact receiving head associated with the fan. 110

7. In an electric hammer, a reciprocating plunger, a fan operated in intermittent rotational impulses upon alternate reciprocations of the plunger, an impact receiving head associated with the fan, and means for returning said head to the normal position after each impact. 115

8. In an electric hammer, a reciprocating plunger, a fan operated in intermittent rotational impulses upon alternate reciprocations of the plunger, an impact receiving head associated with the fan, means for absorbing the shock of said head, and means for returning said head to the normal position after each impact. 120

9. In an electric hammer, a reciprocating plunger, a reciprocatory non-rotational head receiving alternate impacts of the plunger, 125

a spiral driving bar partially rotatable upon movement of the head, a fan, and driving connections between said bar and the fan for imparting intermittent rotational impulses to the fan.

5 10. In an electric hammer, a reciprocating plunger, a reciprocatory non-rotational head receiving alternate impacts of the plunger, a spiral driving bar in engagement with said head and partially rotatable upon movement thereof, a head carried by the driving bar, a fan, a ratchet on the fan, and pawls mounted on the driving bar head and engaging the ratchet.

15 11. In an electric hammer, a reciprocating plunger, an impact receiving head, a spiral driving bar partially rotated upon movement of said head on an impact therewith by the plunger, a head carried by the driving bar, 20 having pawl recesses, a fan including a hub having an internal ratchet circumposed on the driving bar head, and pawls loosely mounted in said recesses and engageable with said ratchet.

25 12. In an electric hammer, a reciprocating plunger, a head receiving alternate impacts of the plunger, means permitting the reciprocation of said head and preventing rotation thereof, a driving bar partially rotatable upon reciprocation of the head, means preventing end-wise movement of the driving bar, a fan operated by the driving bar, and driving connections between said bar and the fan.

30 35 13. In an electric hammer, a casing head including a circular projection, a spiral driving bar rotatable in said head and projection, the bar having a groove and square and circular portions on opposite sides of the groove, means carried by the circular projection partly entering the groove, and a band fitted over the projection to hold said means in place.

40 45 14. In an electric hammer, a driving bar comprising a portion non-circular in cross section partly twisted to form a spiral, and a circular portion, said portions meeting at an annular groove, a pawl head having a semi-circular recess with an extending lip and plane portion, and a pintle in the center of said head.

50 55 15. In an electric hammer, a spiral housing having a bore and a counter bore leaving a shoulder at the juncture of the bores, a spiral driving bar partly occupying said housing, a driving head movable in the counter bore and receiving the end of said bar, and a buffer spring absorbing the shock of the movement of said head and resting 60 against the shoulder between said bores.

65 16. In an electric hammer, a spiral housing having a bore and a counter bore leaving a shoulder at the juncture of the bores, said counter bore having a longitudinal groove, a spiral driving bar partly occupying said

housing, a driving head movable in the counter bore and receiving the end of said bar, a spline carried by said head and slidably in the groove, a buffer spring resting against said shoulder and absorbing the shock of the 70 forward movement of said head, and a spring for returning said head to the initial position.

17. In an electric hammer, a spiral housing including a bore with a counter bore 75 having a longitudinal groove, said bore terminating in a restricted opening, a driving head including a body portion movable in said opening and having a collar movable in the counter bore, a spline carried by the collar and occupying the groove, means for pressing said collar against the shoulder between the restricted opening and the counter bore, and a driving bar including a spiral portion partly occupying one end of the 85 driving head.

18. In an electric hammer, a spiral driving bar having a head with pawl recesses including lips and spring recesses, a fan having a hollow hub receiving said head 90 and provided with an internal ratchet circumposed on the head, a pawl located in each recess including a weighted heel centered below the edge of the lip, a spring in each spring recess pressing the pawl against 95 the ratchet, and a cap closing the hollow hub and holding the pawls in place.

19. In an electric hammer, a casing, a plunger, solenoid magnet coils for reciprocating the plunger, a fan, a spiral driving 100 bar operatively connected with the fan and including a driving head receiving alternate impacts of the plunger to rotate the fan, and a hammer head affixed to the casing including a chamber housing the fan, said 105 chamber having a screened air opening.

20. In an electric hammer, a grooved plunger, solenoid magnet coils surrounding the plunger, a hammer casing in circumferentially spaced relationship to the coils, a 110 fan, means for rotating the fan upon alternate reciprocations of the plunger, to create a current of air through the circumferential space and the grooves of the plunger, and means located at the head of one of the coils 115 adjacent to the fan for dividing the air current.

21. In an electric hammer, a spool having circular segmental pyramidal projections at one end, a plunger reciprocatable in the bore 120 of the spool and having longitudinal grooves on the periphery, coils wound upon the spool, a casing in circumferentially spaced relationship to the spool and coils, and a fan including operating means actuated by the 125 plunger, for directing a current of air toward said projections, for causing the current to flow into said space and through the grooves of the plunger.

22. In an electric hammer, a casing, an 130

attached hammer head having an air chamber, a fan revolvable in said chamber, a casing head having openings admitting the air to the casing, a spool in the casing including a boss having openings coinciding with the casing head openings, and a pyramidal projection formed on the end of the spool and disposed near said coinciding openings for dividing the air current.

5 a medial portion and a bore, said portion having an air chamber surrounding the bore with a perforated web and an air gap communicating with said chamber through the perforations, and a plunger reciprocatable in said bore, having longitudinal air grooves in constant communication with the air chamber.

10 23. In an electric hammer, a spool having

LOUIS PAULERO.
